(57) **CLAIM**

The ornamental design for a vacuum sealer for a wine bottle, as shown and described.

DESCRIPTION

FIG. 1 is a perspective view of a vacuum sealer for a wine bottle showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

In the drawings, the broken lines depict environmental subject matter only that forms no part of the claim.
